UNITED STATES PATENT OFFICE

156,392

CIGARETTE AND TOBACCO-PIPE LIGHTER

Charles K. Wiggins, Seattle, Wash.

Application October 20, 1947, Serial No. 142,021

Term of patent 3½ years

(Cl. D48—27)

To all whom it may concern:

Be it known that I, Charles K. Wiggins, a citizen of the United States and a resident of Seattle, in the county of King and State of Washington, have invented a new, original and ornamental Design for a Cigarette and Tobacco-Pipe Lighter, of which the following is a specification, reference being had to the accompanying drawing, forming a part thereof.

In said drawing:

Figure 1 is a top plan view showing my new design of a cigarette and tobacco-pipe lighter.

Figure 2 is a side elevational view thereof; and Figure 3 is a perspective view thereof.

The side of the device opposite to that shown in Fig. 2 is the same as shown in Fig. 2.

I claim:

The ornamental design for a cigarette and tobacco-pipe lighter, as shown and described.

CHARLES K. WIGGINS.
